GERMICIDAL PREPARATION

Emil Klarmann, Bloomfield, N. J., assignor to
 Lehn & Fink Products Corporation, Bloomfield,
 N. J., a corporation of Delaware

No Drawing. Application January 8, 1936,
 Serial No. 58,141

11 Claims. (Cl. 167—31)

The present invention relates to improvements in germicidal or bactericidal preparations, and more particularly to such preparations containing tertiary butyl-phenol in compound or its alkyl-substituted derivatives. In accordance with the present invention, such compounds are employed as constituents of mixed germicidal preparations, in which they are found to be capable of decidedly enhancing the germicidal efficiency thereof.

By operating in accordance with the present invention, I am able to secure a product of enhanced and uniform bactericidal or germicidal activity, readily and uniformly soluble and dispersible in aqueous media in all proportions. Furthermore, I have found that, by combining, in products in accordance with the present invention, tertiary butyl phenol or the alkyl substituted derivatives thereof, particularly phenols and halogenated or alkylated halogenated phenolic compounds, their combined effectiveness is greatly increased beyond that to be expected or normally found in mixtures of bactericidal compounds.

In accordance with the present invention I may form a bactericidal preparation containing para-tertiary butyl phenol and/or the alkyl substituted derivatives and having uniform bactericidal effectiveness by incorporating the same in dispersed form in an aqueous vehicle. These compounds may be dispersed by diluting their alcoholic solutions with water and as these compounds show a germicidal effect at very low concentrations, the amount of alcohol used may be regarded as negligible for all intensive purposes. The dispersion of the germicidal agents may also be affected by other means, for example, by small proportions of castor oil soap, corn oil soap or the like.

The concentration of the butyl-phenol or its alkyl substituted derivatives such as the butyl cresol in the preparation may be varied within wide limits. I have found a concentration of 5% to be satisfactory for general use, although more or less concentrated products may, of course, be prepared. The product may be diluted to any desired concentration, for use say to 5% or more and even to as low as about 0.017%. In such preparations, containing negligible quantities of alcohol, the para-tertiary-butyl-phenol is found

to have a phenol coefficient of 33.3 with respect to *B. typhosus* (20° C.), using the F. D. A. technique; and the para-tertiary-butyl-meta-cresol is found to have a phenol coefficient of 38.9 with respect to *B. typhosus* under the same conditions. 5

I have also found that in such preparations, para-tertiary butyl phenol or its alkyl-substituted derivatives, in combination with other bactericidal agents of similar character and particularly phenols and alkyl and halogenated phenols, 10 have the peculiar property of enhancing the bactericidal effect of the mixtures. In general and in contradistinction to my discovery, the bactericidal effectiveness of mixtures of bactericides is found to closely approximate the arithmetical means of the substances contained in the mixture, when figured on the basis of the total amount of bactericidal agents present. 15

For example, in aqueous dispersions of the germicide made as above described, and in concentrations as indicated below, the following phenol coefficients with respect to *B. typhosus* are found:

Compound	Min. germ. conc. in			Phenol coefficient	25
	5	10	15 min.		
p. tert.-butyl-phenol.....	1:3000	1:3000	1:3250	33.3	30
p. tert.-butyl-m-cresol.....	1:3500	1:3500	1:4000	38.9	
p. chloro-m-cresol.....	1:750	1:850	1:900	9.4	
p. chloro-phenol.....	1:350	1:375	1:400	4.2	
p. chloro-m-xyleneol.....	1:3000	1:3000	1:3000	33.3	
m-xyleneol.....	1:450	1:450	1:500	5.0	
p-cresol.....	1:200	1:225	1:225	2.5	
U. S. P. cresol.....	1:225	1:250	1:275	2.7	

Mixtures of equal parts of bactericides (not including p. tertiary butyl phenol or p. tertiary butyl-m-cresol) are in general found to have an effectiveness which closely approaches the calculated arithmetical means of the phenol coefficients of these compounds, as disclosed in my prior Patents No. 1,953,413, dated April 3, 1934; and No. 1,984,646, dated December 18, 1934. 40

However, when these substances are combined in a germicidal preparation with para-tertiary butyl phenol and/or alkyl-substituted para-tertiary butyl phenols, their combined effectiveness is much higher than the arithmetical means of the constituents. Thus, in a series of preparations containing para-tertiary butyl phenol or 45

para-tertiary butyl-meta-cresol and another germicidal compound in an aqueous emulsion as hereinbefore described; that is with equal proportions of the germicides included in the mixture, the following results were secured (with respect to *B. typhosus*):

10	Germicides in mixture	Min. germ. conc. in			Phenol coefficient percent		
		5	10	15 min.	Found	Calculated	Inc.
15	p-tert. butyl phenol and p-chloro-m-cresol	1:2250	1:2500	1:2750	27.8	21.4	30
	p-tert. butyl phenol and p-chlorophenol	1:2250	1:2500	1:2500	27.8	18.8	48
	p-tert. butyl phenol and p-chloro-m-xylenol	1:3500	1:4000	1:4000	44.4	33.3	33
20	p-tert. butyl phenol and m-xylenol	1:2000	1:2250	1:2250	25.0	19.2	30
	p-tert. butyl-m-cresol and p-chloro-m-cresol	1:4500	1:5000	1:5000	55.5	24.2	129
	p-tert. butyl-m-cresol and p-chlorophenol	1:3500	1:4000	1:4000	44.4	21.6	106
25	p-tert. butyl-m-cresol and p-chloro-m-xylenol	1:5000	1:6000	1:6000	66.7	36.1	84
	p-tert. butyl-m-cresol and m-xylenol	1:3000	1:3250	1:3250	36.1	22.0	63
	p-tert. butyl-m-cresol and p-cresol	1:2500	1:2500	1:2500	27.8	20.7	34
30	p-tert. butyl-m-cresol and U. S. P. cresol	1:2500	1:2500	1:2500	27.8	20.8	34

A similar increased effectiveness is found in mixtures of phenol (carbolic acid) and para-tertiary butyl phenol or para-tertiary butyl-m-cresol or other alkyl substituted derivatives of the tertiary butyl phenol.

It is thus apparent that para-tertiary butyl phenol and the alkyl substituted derivatives thereof have a marked effect in augmenting the germicidal effectiveness of other germicidal compounds in admixture therewith.

A similar enhancement of effectiveness is found with other bacteria, such as *B. coli*. Mixtures of para-tertiary-butyl-xylenol, para-tertiary butyl ethyl phenol and other alkyl-substituted para-tertiary butyl phenols with other germicides similarly show an enhanced germicidal effectiveness. A similar action may be found in this admixture with other halogenated phenols than those hereinbefore

referred to, such as the corresponding bromo and iodo compounds and other halogenated phenol derivatives.

It is readily apparent that various flavoring or perfuming constituents, soluble substances capable of modifying surface tension, bland oils or the like may be introduced into the aqueous vehicle of the germicidal preparation made in accordance with the present invention, in producing commercial products.

Although the present invention has been described in connection with details of specific examples embodying the same, it is not intended that it shall be regarded as limited thereto, except in so far as included in the accompanying claims.

I claim:

1. A germicidal preparation comprising a tertiary butyl phenol and a phenolic body having germicidal properties.

2. A germicidal preparation comprising a bactericide of the class consisting of para-tertiary butyl phenol and its alkyl substituted derivatives, and a phenolic body having germicidal properties.

3. A germicidal preparation comprising a bactericide of the class consisting of para-tertiary butyl phenol and its alkyl substituted derivatives, and a phenolic body having germicidal properties in an aqueous vehicle.

4. A germicidal preparation comprising para-tertiary butyl phenol and a halogenated phenol.

5. A germicidal preparation comprising para-tertiary butyl phenol and a chloro-phenol.

6. A germicidal preparation comprising para-tertiary butyl phenol and chloro-cresol.

7. A germicidal preparation comprising para-tertiary butyl phenol and chloro-xylenol.

8. A germicidal preparation comprising para-tertiary butyl-meta-cresol and a halogenated phenol.

9. A germicidal preparation comprising para-tertiary butyl-meta-cresol and a chloro-phenol.

10. A germicidal preparation comprising para-tertiary butyl-meta-cresol and chloro-cresol.

11. A germicidal preparation comprising an alkyl substituted derivative of tertiary butyl phenol and a phenolic body having germicidal properties.

EMIL KLARMANN. 50
